UNITED STATES PATENT OFFICE.

JAMES L. NIX, OF HOMER CITY, PENNSYLVANIA.

BROODER.

SPECIFICATION forming part of Letters Patent No. 531,694, dated January 1, 1895.

Application filed September 23, 1893. Serial No. 486,297. (No model.)

To all whom it may concern:

Be it known that I, JAMES L. NIX, of Homer City, Indiana county, Pennsylvania, have made a new and useful Improvement in Brooders, of which the following is a full, clear, and exact description.

The object of the invention is to provide a brooder which shall possess superior advantages with respect to efficiency in use, and it consists in the novel construction and combination of parts hereinafter fully described and claimed.

In the accompanying drawings, Figure 1 is a vertical section of the brooder the section being taken on the line 1—1 of Fig. 2 which in turn is a horizontal section on the line 2—2 of Fig. 1; Fig. 3, a view of either the front or rear wall of the brooder; and Figs. 4 and 5, respectively an end elevation and a top view of said wall; Fig. 6, an inside elevation of one of the side walls of the brooder, and Fig. 7 a top view thereof. Fig. 8 is a vertical section of the roof, its two slopes being detached from each other; Fig. 9, a front elevation of the brooder; Fig. 10, a vertical section on the line 10—10 of Fig. 2, and Fig. 11 a vertical section on the line 11—11 of Fig. 1.

The same letters of reference denote the same parts.

The construction under consideration, generally considered, has four walls, a floor, and a roof.

A represents what may be termed the front wall; B, the opposite or rear wall; C, the left hand side wall; D, the right-hand side wall; E, the floor, and F the roof. The walls are detachably united by means of fastenings such as the hooks G and pins g. The hooks are attached, say to the front and rear walls, and the pins are held in the edges of the adjoining walls, and the relative construction of the walls is such as to permit of the hooks being placed in engagement with the pins, and the walls thereby fastened together.

As the preferred construction in the respect mentioned the front and rear walls, at each end thereof, are each provided with a rabbeted cleat a, and the side walls, at each end thereof, are each provided with a rabbeted cleat c. The cleats, a and c, at each corner of the brooder, are made to interfit substantially as shown, and there is a slot, c', in each cleat

c, to receive the point of the hook G, and the pin g passes through both of the cleats a, c, and when the walls are thus connected they are tied and braced against lateral strains. The walls, toward the lower edge thereof, are each provided with a shoulder, preferably in the form of a cleat b, which, when the walls and floor are joined, rests upon the floor and the walls are thereby upheld, and the wall-edge, b', below the shoulder comes sidewise against the edge of the floor and the walls are thus kept laterally in place with reference to the floor.

The room, H, inclosed by the described floor and walls is preferably raised by means of a foundation composed preferably of the walls I which are suitably united. One, I', of the walls is set in as shown to provide ready access to the hot water heater presently described. The portion, e of the floor is preferably made vertically adjustable, substantially as is indicated by the different positions of the floor shown respectively in the full and in the broken lines. In Fig. 10 a convenient mode of carrying out this feature of the improvement is shown.

e', e', e', are removable blocks inserted in the back wall I, of the foundation, and the inner edge of the floor e can be dropped to rest upon either of said blocks as desired, or a single set of said blocks may be used which can be inserted in the wall I at the desired height therein. The back wall B is usually a closed one as shown. The front wall A may have windows such as shown at a', and which may be hinged at a' to be opened and closed as indicated in Fig. 1, and it has a door, a'', which can be swung as indicated in Fig. 2, to open and close the room H when desired.

The roof, F, is made in the form of two sloping parts f, f', which are connected with the walls of the structure as follows: The part f, which is preferably of sheet metal is provided on its under side with purlins f² and f³. The purlin f² is arranged near the lower edge of the roof-part f and in conjunction with the cleat f⁴ upon the rear wall, forms a groove to receive the upper edge of the rear wall substantially as shown in Fig. 1. The roof-part f'—also has purlins f⁵, f⁶ and f⁷. The purlin f⁵, jointly with the cleat f⁸ upon the front-wall forms a groove to receive the

upper edge of the front wall, and the purlin f^6 , jointly with the purlin f^3 , occupies a notch, f^9 , in the rafters f^{10} of the roof.

In applying the roof to the walls the roof-
5 part f' is dropped into its place first and then
the other roof-part f is dropped into its position,
and in so doing the folded flange f^{11} upon
the part f becomes interlocked with the flange
10 f^{12} upon the part f' , or substantially as shown
in Fig. 1. In this manner it will be seen the
various parts which form the shell of the
structure can be united to form a suitable inc-
15 closure for the purpose in question, and when
it is desired to ship the structure its roof,
walls and floor, and also the foundation, can
be taken apart to be formed into a more compact package.

H' represents a curtained inclosure for the
chickens to go into. It occupies more or less
20 of the brooding chamber H , and it is warmed
directly by means of the coil J which is prefer-
ably a part of a hot water heating appa-
ratus whose boiler is shown at j . The prefer-
able means for heating the boiler is a lamp
25 K and the heating apparatus preferably in-
cludes a hot air chamber L which rises into
the chamber H . The lamp rests in the lower
part of said hot air chamber and the heat of
the lamp is applied directly to the boiler,
30 which is preferably of the inverted cup-shape
shown, and thence the heat rises above the
boiler into the upper part of the chamber L
and ultimately into the escape flue l , which
extends upward through the roof F . The
35 chamber L is preferably made in two parts,
a lower part l' , which is attached to the floor E ,
and an upper part l^2 which is slipped from
above onto the lower part l' . The escape l
preferably extends downward into the cham-
40 ber L , substantially as shown, and said ex-
tension l^2 is, together with the chamber itself,
detachable from the escape l . This enables
the parts of the chamber L to be separated
from each other. In this manner the heat of
45 the lamp is applied in two ways to the cham-
ber H , namely: by means of the hot water
heating apparatus, and by means of the cham-
ber L . The water supply in the boiler is

5 maintained by means of the rising pipe j'
and the hopper j^2 . The coil is connected with
the boiler at different levels, substantially as
shown to provide for the proper circulation
of the water through the apparatus.

55 M represents a ventilation-opening in the
wall of the chamber H .

By making the floor of the brooding cham-
ber vertically adjustable substantially as de-
scribed additional room can be provided from
time to time for the chickens as they enlarge
in size. 60

N represents a step leading to the brooding
chamber.

A convenient way of forming the inclosure
II' is to utilize the coil J as a support for the
inclosure-top h , and attach a curtain h' to the 65
top h as shown.

I claim—

The brooder comprising the closure, the
cylinder or chamber consisting of the lower
section fixed to, and extending above and 70
below, the floor of the closure and the upper,
main section having its lower edge compass-
ing the upper edge of the lower section and
having a central pendent tube therein, a
combustion outlet pipe forming an extension 75
of said pendent tube, an inverted cup-shaped
boiler arranged in the upper part of said
lower section and having connected thereto
near its lower end, an elbow-pipe, an ele-
vated automatic water-feeding tank, or res- 80
ervoir with its vertical feed-pipe connecting
with said elbow-pipe of the boiler, a heating
pipe coil having connection with the upper
part of said boiler and connection with the
lower end of said vertical feed-pipe of the 85
water-tank, a curtained compartment or cham-
ber; with its top resting upon said pipe-coil,
and a heater below said boiler, substantially
as set forth.

Witness my hand this 13th day of Septem- 90
ber, 1893.

JAMES L. NIX.
